UNITED STATES PATENT OFFICE.

FRIEDRICH KÖNIG, OF MUNICH, GERMANY.

REFRIGERATING CHAMBER.

Application filed August 27, 1921. Serial No. 496,574.

To all whom it may concern:

Be it known that I, FRIEDRICH KÖNIG, citizen of Germany, residing at Munich, Bavaria, Germany, have invented certain 5 new and useful Improvements in a Refrigerating Chamber (for which I have filed applications in Germany, August 21, 1917; England, August 20, 1917; France, July 9, 1920; Spain, October 28, 1920; Austria, 10 December 15, 1920; Hungary, August 14, 1920; and Czechoslovakia, July 8, 1920); and I do hereby declare the following to be a full, clear, and exact description of the invention, such as will enable others skilled 15 in the art to which it appertains to make and use the same.

This invention relates to refrigerating chambers of the type cooled by water and having a lining of stone or earthenware or 20 the like.

According to this invention, the stone-ware lining consists of plates attached to a flexible material, such as cloth, guttapercha, thin metal or the like, and their edges are 25 bevelled, at an angle of 45° to the face attached to the said material. This arrangement facilitates the insertion of the stone-ware into the box or chamber, and the back-ing of flexible material improves the insu- 30 lation. The slabs may have ducts therein, as will be described hereinafter.

The invention is illustrated in the annex drawing, in which Fig. 1 is a vertical sec-tion of the refrigerator, Figs. 2 and 3 being 35 sections on the line A—B of Fig. 1, viewed from the bottom and top respectively.

The chamber shown comprises a double walled inner container, having walls a and a' , between which the water flows. This 40 container is inside a wooden box b , and be-tween it and the box walls there are con-tiguous stone slabs c attached to sheet or strip, or sheets or strips, of the flexible ma-terial d . The edges of the slabs are bevelled 45 as already mentioned. In the construction shown all the slabs for the side walls and top are attached to one sheet, bent at e , the corner slabs fitting against each other as shown. The slabs for the floor and back 50 may be attached to another sheet. The bevelled edges form a network of channels f , containing air, and the inner container a a' has indentation h facing and enlarging 55 these channels. The slabs have ducts g therein, opening into the said channels and joined end to end at the corners. Water

enters the chamber between the walls a and a' through a pipe a^2 disposed at the lower portion thereof and after circulating through the chamber it passes off through a vent a^3 60 arranged in the top of the chamber in the known manner.

The attachment of the slabs to flexible material facilitates the fitting of the slabs into the box, and the air channels improve 65 the cooling effect and keep the box dry.

It should be noted that a container i for ice may be inserted into the lower part of the refrigerator. Thus partly by reason of the completely surrounding water cooled 70 walls of the refrigerator and the ice con-tainer, partly by reason of the stones, and further by reason of the air in the ducts f and g as well as in the ice container, a heat exchange occurs which causes further 75 cooling of the contents of the refrigerator. The valves k may be opened according to the requirement to effect communication be-tween the air in the ice container and the air in the ducts f and g .

What I claim is:

1. A refrigerator having a lining of stone-ware slabs flexibly connected together and provided with bevelled adjacent edges, each slab being further provided with an air 85 duct communicating with the space between the said bevelled edges.

2. In a refrigerator, the combination of a provision chamber with hollow walls through which water is circulated, of flex-ibly mounted stoneware slabs disposed about said walls, an air circulating space being provided between the adjacent edges of the slabs and the walls, said air spaces being ar-ranged by the edges of the slabs which are 90 bevelled at an angle to the faces thereof at-tached to the flexible material, an inlet pipe and outlet pipe for the hollow walls, and a cooling chamber at one end of said refrig-erator and in communication with said air 95 spaces, substantially as described.

3. In a refrigerator, the combination of a provision chamber surrounded by a water jacket having inlet and outlet openings at opposite ends, of a series of stoneware slabs 105 disposed about said jacket, flexible material to which said slabs are secured, said slabs being provided with bevelled edges cut at 45 degrees from the flexible material out-wardly to form air spaces therebetween, 110 each slab being provided with an air pas-sage extending through from opposite

bevelled edges, whereby communication may be established between the spaces defined by the bevelled surfaces, a cooling chamber at one end of the refrigerator in communication with the air spaces, and valves disposed between the cooling chamber and the remaining portion of the refrigerator.

4. In a refrigerator, the combination of a water jacket in which the water is adapted to be circulated, the outside walls of the jacket being provided with uniformly spaced depressions, of a filler of stoneware slabs interposed between the water jacket and the wall of the refrigerator, each slab

being provided with bevelled edges cut at 15 45 degrees and disposed so as to coincide with the depressions in the jacket and a communicating passage extending through from opposite faces of the bevelled edges thereof, the said passages being disposed so 20 as to be aligned with the adjacent passages of the other slabs.

In testimony whereof I hereunto affix my signature in the presence of two witnesses.

FRIEDRICH KÖNIG.
